IGNITION CIRCUIT

Raymond J. Miller, Detroit, Mich.

Application June 21, 1943, Serial No. 491,584

3 Claims. (Cl. 315—213)

1

This invention relates to engines, and more particularly to improved ignition systems for engines.

In conventional ignition systems, the voltage is stepped up and is transmitted through single high tension leads to the spark plugs to fire the combustible charge in the cylinder of the engine. Single electrode spark plugs are employed, and the circuit is completed by enclosing the entire ignition system in metallic covers, or by utilizing the engine as a ground to complete the circuit. The entire engine and vehicle thus becomes a part of the ignition circuit and acts as a variable capacitor.

In accordance with conventional practice, a single high tension coil is used for each engine. In multi-cylinder engines, this coil is frequently over-taxed because the reluctance will not permit the coil to completely collapse before the next impulse is imposed on it to provide the necessary high voltage spark to fire the next cylinder when the engine is operating at high speed. In certain high speed engines it has been necessary to employ two or more high tension coils per engine to prevent over-taxing the coils.

Considerable current from the high tension coils is lost before reaching the spark plugs through leakage from the high tension wires connected to the spark plugs. The efficiency of ignition systems now in use is therefore considerably below that desired.

In ignition systems as presently employed, undesirable signals are emitted whenever the engine is running. These undesirable signals are emitted from:

1. The sparking of high tension current jumping from the rotating distributor arm to the successive distribution points.
2. The sparking at the spark plug electrodes.
3. The leakage from the high tension wires leading from the distributor to the spark plugs.

In military vehicles, the enemy can establish listening stations and readily pick up these undesirable signals emitted from the ignition system. The exact location of a vehicle or a convoy of vehicles can thus readily be ascertained by triangulation from spaced listening stations. Accurate gun fire can then be brought to bear on the vehicle or convoy of vehicles.

These undesirable signals emanating from the ignition system interfere with radio communication, both sending and receiving, and cause distortion of the images in the operation of television sending and receiving apparatus.

Efforts have been made to overcome these ob-

2

jectionable features by using suppressors hooked within the circuits; by the use of shielding surrounding the wires and electrical units, and by bonding the component parts of the vehicle together to maintain good electrical contacts between all parts of the vehicle. These efforts have not been very successful because of the expense and time required in their installation and the difficulty of maintaining them in proper working condition.

An object of this invention is to provide a closed circuit ignition system wherein the above enumerated disadvantages are eliminated.

A further object of the invention resides in the provision of an improved ignition system wherein low voltage current is transmitted by a distributor to a compact transformer associated with each spark plug of the engine.

Another object is to provide an ignition system for an engine wherein dual electrode spark plugs insulated from the engine are supplied by high voltage circuits, each of which is completely contained within its associated spark plug.

Still a further object of the invention is to provide a distributor to induce low voltage current in such a manner that a spark gap capable of transmitting undesirable signals is not present.

Yet another object resides in the provision of a closed circuit ignition system wherein low voltage current is induced and is transmitted through low tension wires to small transformers positioned on dual electrode spark plugs insulated from the engine.

A further object is to provide an ignition system wherein transformers having primary and secondary windings wound in a bell shaped manner extend down over the body portions of dual electrode spark plugs to produce directed magnetic fields to provide controlled electric sparks at the electrodes of the plugs, and produce a blow-out condition at the spark gap to provide sharper more controlled points of ignition.

Another object of the invention resides in the provision of an ignition system wherein it is unnecessary to employ continuous shielding, bonding or suppressors to prevent the transmission of undesirable signals capable of indicating the location of the vehicle and interfering with radio or television transmission or reception.

Other objects and advantages of this invention will be apparent from the following detailed description considered in connection with the accompanying drawings, submitted for purposes of illustration only and not intended to define the scope of the invention, reference being

had for that purpose to the subjoined claims.

In the drawings wherein similar reference characters refer to similar parts throughout the several views:

Before explaining in detail the present invention it is to be understood that the invention is not limited in its application to the details of construction and arrangement of parts illustrated in the accompanying drawings, since the invention is capable of other embodiments and of being practiced or carried out in various ways. Also it is to be understood that the phraseology or terminology employed herein is for the purpose of description and not of limitation.

Figure 1 is a diagrammatic view illustrating the invention as applied to a self-contained closed circuit ignition system for a six cylinder internal combustion engine. A highly concentrated magnetic field type permanent magnet 10 is carried by a rotor arm 12 driven by a shaft 14 geared or otherwise suitably connected to the engine.

The magnet 10 has suitable pole pieces 16 and 18 adapted to rotate with reference to spaced induction coils 20, 22, 24, 26, 28 and 30. As the pole pieces of the magnet sweep past these induction coils, electric current is induced therein. The current thus induced is directed through wires 32 and 34 to opposite ends of primary coils 36 mounted on spark plugs 40, 42, 44, 46, 48 and 50 projecting into the cylinders of the engine.

As illustrated in Figs. 1 and 7 opposite ends of the primary coils 36 are connected to opposite ends of the induction coils 20, 22, 24, 26, 28 and 30 respectively. Secondary coils 52 are preferably concentrically mounted on the primary coils 36. Opposite ends of the secondary coils 52 are connected to spaced electrodes 54 and 56 of the spark plugs 40, 42, 44, 46, 48 and 50 positioned within the cylinders of the engine.

Current is thus generated by movement of the magnet 10 relative to the induction coils 20, 22, 24, 26, 28 and 30. This generated current is transmitted to the primary coil 36 to energize the secondary coil 52 by induction. The secondary coil 52 amplifies the charge and it is discharged in the engine cylinders between the electrodes 54 and 56 of the spark plugs.

In conventional ignition circuits a spark is impressed between a central electrode of the spark plug and an outer electrode secured to the shell of the spark plug threaded into the cylinder of the engine. The electric current to develop the spark is supplied by a battery or a magneto having one terminal connected or grounded to the frame of the vehicle or to the body of the engine. The other terminal of the battery or magneto is connected through suitable condenser coils and distributors with the central electrode of the spark plug. When the spark is induced between the electrode of the spark plug, the electric circuit is thus completed to the battery or magneto through the frame of the vehicle or the body of the engine. The potential of current is therefore raised throughout the vehicle each time a spark plug is fired.

In my system a closed electric circuit is formed between the induction coils 20, 22, 24, 26, 28 and 30 and therein associated primary coils 36 operably connected thereto through the wires 32 and 34. The potential of the current developed by the magnet 10 or the electric coil substituted therefor is very low and will have negligible effect insofar as raising the potential of the current throughout the vehicle is concerned. A confined

circuit is formed between the secondary coils 52 and the electrodes 54 and 56 of their associated spark plugs 40, 42, 44, 46, 48 and 50 when the secondary coils are fired by current induced by their associated primary coils. The current induced to fire the spark in the plugs will follow the path of least resistance. Since the outer electrode 56 is insulated from the shell or body of the spark plug and thus from the engine, the spark will be induced between the electrodes 54 and 56 and virtually no current will flow from the outer electrode 56 to the shell of the plug. The potential of the current throughout the vehicle is therefore not raised to any material extent.

Moreover, as each high tension circuit is self-contained in its respective spark plug, and as each plug has its own metallic casing, there is no possibility of the escape of electromagnetic emanations of radio frequencies; hence a radio-shielding effect is inherent in the disclosed structure, yet without the necessity of enclosing the entire ignition system in a continuous metallic covering, and without the provision of any shielding whatever for the low tension leads 32, 34, or the coils 20, 22, 24, 26, 28 and 30.

Referring now to Figs. 2 to 7 for more details of the mechanism, it will be noted that the induction coils 20, 22, 24, 26, 28 and 30 are mounted in a casing 58 surrounding the shaft 14. The wires 32 and 34 from opposite ends of the induction coils are directed through the walls of the casing 58 by means of suitable connectors 60. The wires 32 and 34 from the induction coils to the primary coils 36 are preferably braided to prevent the formation of line induction developed when wires run parallel to each other for a considerable distance.

Assuming counter-clockwise rotation of the magnet 10 as viewed in Fig. 3 and illustrated by the arrow 62, the induction coils 20, 22, 24, 26, 28 and 30 should be successively connected by the wires 32 and 34 to the coils associated with the spark plugs 40, 42, 44, 46, 48 and 50 in the desired firing order of the cylinders of the engine. For example if the desired firing order of a six cylinder engine were 1-5-2-4-3-6, the coils 20, 22, 24, 26, 28 and 30 should be connected to the coils of the spark plugs 40, 42, 44, 46, 48 and 50 to fire the plugs in the desired order as the magnet 10 rotates.

Any suitable means may be provided to vary the time of inducing the spark between the electrodes 54 and 56 of the spark plugs with reference to the position of the piston in the cylinder of the engine. One desirable form of control means comprises mounting the arm 12 on a plate 64 carried by the shaft 14 to have limited to rotational movement therewith. Yielding means such as a spring 66 may be provided to maintain the arm 12 in a retarded position. A centrifugally actuated member 68 having a weight 70 may be pivotally mounted on the plate 64 at 72. The member 68 may be provided with a hook 74 to engage an arm 76 carried by the arm 12 to oscillate the arm 12 in the direction of the arrow 62 as the speed of rotation increases to advance the spark or the time of inducing the spark between the electrodes 54 and 56 with reference to the position of the piston in the cylinder. Suitable stops 78 and 80 carried by the plate 64 may be provided to limit the movement of the centrifugally actuated member 68.

The induction coils 20, 22, 24, 26, 28 and 30 are preferably formed with a relatively large num-

ber of wires 82 resulting from a high number of turns about a core 84 to develop the desired current as the magnet 10 is moved past the coils.

The core 84 may be supported in any suitable insulating material 86, and the wires 82 may be wrapped about the core 84 and insulating material 86, and be maintained in position by means of suitable guides 88 having longitudinally extending flanges 90. Suitable supporting brackets 92 may engage the flanges 90 to secure the coils in position within the casing 58.

The core 84 is preferably formed of a plurality of core pieces 94 to provide a multiple current surge and cause a repetition of firing in the cylinder of the engine. Where the core pieces 86 are formed of closely spaced laminated strips, a stronger more highly concentrated magnetic field will be produced. Greater possibility of firing the charge in the cylinder is thus insured.

For more economical installations where high performance is not essential a single core member 96 as illustrated in Fig. 5 may be employed rather than the multiple core pieces 94 as illustrated in Figs. 3 and 4. It will be understood that where a single core member 96 is thus used, a single spark will be induced in the cylinder of the engine with the possibility of the back E. M. F. firing again if the suppression of the spark is not too great, rather than the multiple spark developed where multiple cores are employed.

The permanent magnet 10 is preferably formed of laminations 98 as illustrated in Fig. 6 to induce higher current as the magnet passes the induction coils. It will of course be understood that the magnet 10 and the core pieces 94 of the induction coils may be formed of sintered powdered or solid metal if desired.

One desirable form of dual electrode spark plug having the primary and secondary coils mounted thereon is illustrated in detail in Figs. 7 and 8. The spark plug 40 comprises a base member 100 having threads 102 whereby the plug may be secured in the combustion chamber of an engine, and a wrench receiving portion 104 preferably of hexagonal shape.

The inner electrode 54 preferably has a body portion 106 and is provided adjacent its bottom end with an enlarged outwardly flaring portion 108. The outer electrode 56 is concentrically mounted on the inner electrode 54 and is insulated therefrom by suitable insulators 110, 112 and 114, and is insulated from the base member 100 by means of a suitable insulator 116.

The insulator preferably extends over the entire cylindrical body portion 106 of the inner electrode 54, and may be formed of any suitable material such for example as mica. The insulators 112 and 114 may be concentrically mounted on the insulator 110 and may for example be formed of ceramic material.

It will be noted that the lower body portion of the outer electrode 56 is flared outwardly in the base member 100. The insulator 116 may for example be formed of mica and may be tapered in accordance with the taper of the lower body portion of the outer electrode 56 whereby the unit consisting of the inner and outer electrodes 54 and 56 with the insulators 110, 112, 114 and 116 may be securely bonded to the base member 100 by means of upper and lower flanges 118 and 120 positioned to overlie the insulator 116.

Discs 122 and 124 formed of copper or other suitable material may be interposed between the insulator 112 and the lower surface of an inwardly directed flange 126 formed on the outer

electrode 56, and the insulator 114 and the upper surface of the flange 126 to take up mechanical differential in the manufacture of the parts.

The upper end of the outer electrode is provided with threads 130 to receive the base of a coil supporting member 131 surrounding the plug. The member 131 is formed adjacent its upper end with a section of reduced diameter to receive an insulator 133 formed of any suitable material such as Bakelite.

Wrapped about the insulator 133 and the lower portion of the member 131 is the primary coil 36 wound with relatively coarse wire 136 as is customary. Surrounding the primary coil 36 is a core 138 formed of iron or steel or other suitable electrical conducting material.

The secondary coil 52 preferably formed of smaller wire 148 than the wire 136 of the primary coil 36 is wrapped about the core 138. The primary and secondary coils 36 and 52 are covered at the top by means of an insulator 142 formed of Bakelite or other suitable material having a section 144 of reduced diameter to fit within the core 138. A casing 146 is provided to overlie the insulator 142 and secondary coil 52 to function as an additional core to assist the core 138. The casing 146 is suitably secured to an upwardly directed flange 154 carried by the coil supporting member 132.

The wires 32 and 34 from the induction coils 20, 22, 24, 26, 28 and 30 are connected to opposite ends of their associated primary coils 36. The wire 32 is as illustrated in Fig. 9 connected through a spring clip 145 to a central pole 146 positioned on the insulator 142 and connected through a wire 148 embedded in the insulator 142 to one end of the primary coil 36.

The other wire 34 may be connected through a spring clip 147 to a furl 150 positioned on the insulator 142 and connected through a wire 152 extending through the insulator 142 to the other end of the primary coil 36. The furl 150 may be separated from the pole 146 by means of a suitable portion 154 of the insulator 142, and from the casing 146 by means of a suitable insulator portion 156. A casing 149 receives the wires 32 and 34 and insures proper insulation of the contact clips 145 and 147.

Each of the primary coils 36 is excited by an inductive surge current from its associated induction coil as the magnet 10 sweeps past the induction coil. The core member 136 interposed between the primary and secondary coils 36 and 52 respectively, being of bell shaped contour, and the core 148 surrounding the secondary coil 52 concentrate the magnetic lines of force. This concentrated electrical field induces a strong induction current in the secondary coil 52.

Opposite ends of the secondary coil 52 are connected to the inner and outer electrodes 54 and 56 of the spark plug 40. One end of the coil 52 may be connected through a wire 158 embedded in the insulator 142 to a resistor 160 engaging the end of the cylindrical body portion 106 of the central electrode 54.

The resistor 160 may be guided in a portion 162 of reduced diameter of the insulator 133, and may be yieldingly urged into engagement with the body portion 106 of the central electrode 54 by means of a spring portion 164 of the wire 158. The resistor 160 may be made of carbon or other good resisting material. Where a resistor similar to that illustrated is employed, the electrodes 54 and 56 of the plug 40 will not be subjected to such prolonged current and will therefore be

longer lived because the resistors tend to smooth out the electrical surge.

The other end of the secondary coil 52 is connected to the coil carrying member 131 as illustrated at 166. The flow of current is preferably from the secondary coil 52 through the central electrode 54, thence across the spark gap 168 to the outer electrode 56 and back to the secondary coil 52.

10 The operation of this embodiment of the invention is as follows: Current, induced in the induction coils by rotation of the magnet 10 is transmitted through the wires 32 and 34 to the high tension coil or transformer associated with each spark plug to increase the voltage that provides a high potential spark. The current from the induction coils produces an inductive surge current in the primary coil 36, and this current is concentrated by the core 138 and the outer shell 146. The secondary coil 52 is thereupon energized whereupon a high intensity spark is produced. This high potential spark is directed through the electrodes to produce the desired spark in the spark gap 168 to fire the charge in the cylinder, and the circuit is thereafter completed by passing through the other electrode back to the secondary coil.

30 The inner and outer electrodes 54 and 56 and the coil supporting member 131 may be formed of any suitable material having good electrical conducting characteristics, such for example as steel.

35 It will be noted that this spark plug is thoroughly shielded against moisture and is advantageously insulated to prevent undesired electrical losses or short circuiting. Greater voltage can therefore be exerted to fire the charge in the cylinder of the engine.

40 The entire circuit is self-contained and it is not necessary to use the engine or any other part of the vehicle as a ground. Since the vehicle is not used as a ground for the ignition circuit it is not effective as a variable capacitor, and the necessity for bonding the component parts of the vehicle together is entirely eliminated.

45 In view of the fact that low voltage current is transmitted to the transformers associated with the spark plugs, it is unnecessary to employ shielding on the spark plug wires to prevent leakage from the high tension wires as is now customary.

50 No spark gap is present in the distributor as the low intensity current is induced in the induction coils by movement of the magnet with reference to the coils. Undesirable signals from this source are therefore eliminated. The spark gap between the electrodes of the spark in the combustion chambers being insulated from the engine will not transmit undesirable signals as is customary with presently used ignition systems.

55 Fig. 10 illustrates a somewhat modified form of spark plug over that disclosed in Figs. 7 and 8. Corresponding parts have therefore been given 60 corresponding reference numerals with the addition of 100.

65 It will be noted that the inner electrode 206 is shorter than the inner electrode of the plug illustrated in Figs. 7 and 8, and that the outer electrode 226 is provided with a plurality of spaced heat radiating fins 270, positioned beneath the threaded portion 230.

70 The lower portions of the inner and outer electrodes 206 and 226 have parallel, preferably angularly disposed side walls 272 and 274 respectively

to define there-between a spark gap 276. The parallel spark gap 276 gives greater opportunity for the plug to clear itself in the event of fouling and will therefore frequently prevent short circuiting of the plug.

A transformer of the general type illustrated in Fig. 7 may be employed with the plug illustrated in Fig. 10, or it may be connected to conventional magneto or distributor circuits. When so used, the central electrode 206 is preferably connected to the high tension lead, and the outer electrode 226 is grounded back to the electrical source. A confined circuit is thus provided in conventional magneto or distributor circuits whereupon it is unnecessary to employ the body of the engine or vehicle to complete the circuit from the source of electric current such as a battery or magneto.

Figs. 11 to 13 illustrate an embodiment of the invention which is similar in many respects to that illustrated in Figs. 1 to 6. Corresponding parts have therefore been given corresponding reference numerals with the addition of 100.

In this embodiment, the invention is applied to a system wherein a battery 200 is employed as the source of electric current. One wire 202 from the battery is connected through leads 204 and 206 preferably embedded in the housing 158 with a centrally disposed spring pressed contact 208. The contact 208 engages a cooperating contact member 210 embedded in a distributor arm 212 driven by the shaft 114.

The arm 212 carries an electro-magnet 216 having a core 218 adapted to move between cooperating pole pieces 222 and 224 of the induction coils 120, 122, 124, 126, 128 and 130 operably connected through the wires 132 and 134 to the transformers associated with the spark plugs 40, 42, 44, 46, 48 and 50 of the engine as illustrated in Fig. 1. The pole pieces 222 and 224 are portions of the cores of the induction coils, and as illustrated in Fig. 13 may be of laminated construction. The induction coils 120, 122, 124, 126, 128 and 130 may be suitably attached to the housing 158 by suitable brackets 226.

The electro-magnet 216 comprises a suitable core 218 and a coil 228 wrapped about the core. One end of the coil 228 is connected through a wire 230 with the contact member 210, and the other end of the coil 228 is connected through a wire 232 with a contact ring 234. The contact ring 234 embedded in the rotating arm 212 is connected through a spring pressed slip contact 236 and leads 238 and 240 preferably embedded in the housing 158 with a terminal 242 operably connected to the battery 200 through a suitable breaker mechanism operated by a cam 244 rotating with the arm 212.

The cam 244 having a number of lobes 246 corresponding with the number of spark plugs to be fired is interposed between the shaft 114 and the arm 212 to be actuated by the automatic spark advance mechanism 168 and rotate with the arm 212.

A plate 248 positioned in the housing 158 is provided with an electrical contact point 250 carried by a bracket 252 connected with the terminal 242 by a wire 253, an arm 254 pivotally mounted at 256 on the plate 248 is provided with an electrical contact point 258 adapted to be actuated by the cam 244 to engage the contact point 250 when the core 218 of the electromagnet 216 carried by the arm 212 is substantially aligned

with the poles 222 and 224 of the induction coils 120, 122, 124, 126, 128 and 130.

The arm 254 is provided with a spring 260 engaging an electrical connection 262 positioned in the housing 158, and connected to the battery 200 through a wire 263, to yieldingly urge the arm 254 to rotate about its pivot 256 to engage the contacts 250 and 258. An actuating projection 264 carried by the arm 254 is adapted to engage the lobes 246 of the cam 244 to maintain the contacts 250 and 258 separated except when the electromagnet 216 is aligned with one of the induction coils.

The operation of this embodiment of the invention is as follows: Current flows from the battery 200 through the wire 202 and leads 204 and 206 to the spring pressed contact 208 engaging the contact member 210 embedded in the rotating arm 212. The contact point 210 is connected with one end of the coil 228 of the electromagnet 216 through a wire 230, and the other end of the electromagnet is connected through the wire 232 with the circular contact ring 234 embedded in the rotating arm 212. Current from the contact ring 234 passes through the spring pressed contact 236 and leads 238 and 240 to the terminal 242. Current from the terminal 242 passes through the wire 253 to the bracket 252 carried by the plate 248 having the contact point 250 carried thereby.

When during rotation of the arm 212 the electromagnet 216 is aligned with the pole pieces 222 and 224 of one of the induction coils 120, 122, 124, 126, 128 and 130, the cam 244 engaged by the actuating projection 264 of the arm 254 permits the contact 258 carried by the arm 254 to engage the contact 250 whereupon the circuit through the arm 254, spring 260 and wire 263 is completed to the battery 200. Current then flows through the coil 228 of the electromagnet 216 to successively induce a charge in each of the coils 120, 122, 124, 126, 128 and 130. This induced charge is transmitted through the wires 132 and 134 to the transformer illustrated in Fig. 7 as being associated with each of the spark plugs in the combustion chambers of the engine.

It will be apparent that the battery 200 is connected to the coil 228 of the electromagnet 216 only when the core 218 of the electromagnet 216 is aligned with the pole pieces 222 and 224 of one of the induction coils. The cam actuated distributor mechanism operates to provide a sharp timing whereupon low voltage current may be directed to the transformer associated with each of the spark plugs at the precise instant when it is desired to fire the charge in the combustion chamber of the engine. The automatic spark advance mechanism 168 operates to vary the time of firing the charge in accordance with variations of the speed of rotation of the engine whereupon the most desirable conditions of firing the charge may be attained.

If desired the electromagnet 216 and the induction coils associated therewith may be of such proportions that sufficiently high intensity current is induced that separate transformers on the spark plugs are unnecessary.

Figs. 14 and 15 illustrate a further modified form of the invention wherein a battery is employed as the source of electric current. An engine driven shaft 300 is mounted in a housing 302 having a plate 304 positioned therein. The shaft 300 drives a cam 306 having spaced lobes 308 corresponding in number with the number of

spark plugs to be fired through an automatic spark advance mechanism 310.

An arm 312 pivoted on the plate 304 at 314 is yieldingly urged toward the arm 306 by an electrical conducting spring 316 connected through a terminal 318 in the housing 302 with one terminal 320 of a battery 322. The arm 312 has a projection 324 to engage the lobes 308 of the cam 306, and a contact point 326 to engage a contact point 328 carried by a bracket 330 mounted on the plate 304. The bracket 330 has a spring contact 332 engaging a ring 334 carried by a member 336 mounted on the cam 306. The ring 334 is connected through a contact 338 with a spring pressed contact 340 mounted in a portion 341 of a cap 343 and connected through suitable leads 342 with one end of primary coils of transformers 344. A number of transformers 344 corresponding with the number of spark plugs to be fired are mounted in the housing 302.

The member 336 is provided with another contact member 346 adapted to engage spaced contact members 348 carried by arms 350 projected inwardly from the walls of the housing 302. A number of arms 350, having contact points 348 to be engaged by the contact member 346, corresponding with the number of spark plugs to be fired are employed. The arms 350 are electrically connected by means of a connector 352, and are connected through the housing 302 with the other terminal 354 of the battery 322.

The contact member 346 carried by the member 336 is connected through a spring pressed slip contact 356 and suitable leads 358 with the other side of the primary coils of the transformer 344. Opposite ends of the secondary coils of the transformers 344 are connected through suitable leads 360 and 362 with the transformers associated with each spark plug. If desired the leads 360 and 362 may be connected to the spaced electrodes of the spark plugs 40, 42, 44, 46, 48 and 50 illustrated in Fig. 1.

The operation of this embodiment of the invention is as follows: As the member 336 carried by the shaft 300 rotates, the lobes 308 of the cam 306 permit the contact members 326 and 328 to close at the time it is desired to fire a spark in one of the spark plugs of the engine. When the contacts 326 and 328 engage, electric current flows from the battery 322 through the terminals 320 and 318, spring 316, arm 312 contacts 326 and 328, bracket 330 spring contact 322, ring 334, contacts 338 and 340 and lead 342 to one end of the primary coil of one of the transformers 344.

At the time the lobes 308 of the cam 306 permit the contacts 326 and 328 to close, the contact member 346 positioned in the member 336 interconnects the contact member 348 of one of the arms 350 to complete the circuit from the battery 322 terminal 354 and lead 358 to the other side of the primary coil of one of the transformers 344. The current thus induced in the primary coil of one of the transformers 344 energizes the secondary coil of the transformer and the current from the secondary coil is transmitted through the leads 360 and 362 to the primary coil 36 of one of the spark plugs illustrated in Fig. 7.

It will be understood that a transformer 344 is used for each of the spark plugs to be fired. Where this embodiment of the invention is employed, the current transmitted to the transformer associated with each spark plug is stepped up to transmit relatively high voltage to the transformer associated with each spark plug.

The transformers 344 may be of any desired size with respect to the transformers associated with each spark plug to provide the desired intensity of spark between the electrodes of the spark plug. For example the voltage of the current may be slightly increased by the transformers 344 and materially increased by the transformers associated with the spark plugs. The voltage may if desired be considerably increased by the transformers 344, and then be somewhat further increased by the transformers associated with the spark plugs, or the voltage may be increased substantially uniformly or in any desired ratio by each of the transformers.

It will of course be apparent that if desired the transformers associated with the spark plugs may be dispensed with and the leads 360 and 362 from the transformers 344 connected directly to the electrodes of the spark plugs. High voltage current would then be transmitted to the spark plugs through a closed circuit system wherein the engine would not be employed as a ground for the circuit.

Fig. 16 illustrates an adapter to connect with the leads 360 and 362 from the transformers 344. The lead 360 may be connected with a pole piece 364 centrally disposed in an insulating grommet 366. The lead 362 may be connected with a ring 368 concentrically mounted in the grommet 366 relative to the pole piece 364 to be insulated therefrom. The pole piece 364 engages a contact member 370 connected for example to one end of the secondary coil of one of the transformers 344. The ring 368 may be engaged by a spring clip 372 connected for example to the other end of the secondary coil of the transformer 344. The pole piece 364 and the ring 368 may be connected to wires 374 and 376 respectively leading through a conduit 378 to the electrodes of a spark plug or to the transformer associated with a spark plug.

Fig. 17 illustrates a modified form of connector wherein one of the wires 374 housed within the casing 378 is connected through a spring clip 380 with a centrally disposed contact or electrode member 382. The other wire 376 is connected to a ring 384 embedded in a body portion 386 of the connector to be insulated from the clip 380. The ring 384 may be engaged by a spring clip 388 connected to the other contact or electrode member and concentrically mounted relative to the contact 382 to be insulated therefrom. A cap 390 engaging a shoulder 392 of the body portion 386 may be threaded at 394 on a body portion 396 surrounding the contact or electrode members 382 and 388 to seal the connections against the entrance of moisture.

The embodiment of the invention illustrated in Fig. 18 is similar in many respects to that illustrated in Figs. 14 and 15, corresponding parts have therefore been given corresponding reference numerals with the addition of 100.

The leads 442 and 458 connected through the spring pressed contacts 440 and 456 with the battery through the distributor mechanism connect with terminals 470 and 472 leading to the transformers associated with the spark plugs of the engine as illustrated in Fig. 1. In this embodiment of the invention, low voltage current from the distributor is directed to the transformers of the spark plugs and is stepped up there to provide the desired high intensity spark between the electrode of the spark plug to ignite the charge within the cylinders of the engine.

Fig. 19 illustrates one desirable method of connecting wires 375 and 377 to the spaced electrodes of a dual electrode spark plug. The wires 375 and 377 may be connected to the transformers 344 illustrated in the embodiment of Figs. 14 and 15, or one of the wires 375 or 377 may be connected to the high tension lead of a conventional magneto or distributor circuit, and the other of the wires 375 or 377 may be grounded back to the source of electric current. The wires 375 and 377 may project into a housing 381 mounted on a dual electrode spark plug 340.

The spark plug illustrated in Fig. 19 is similar in many respects to that illustrated in Fig. 7. Corresponding parts have therefore been given corresponding reference numerals with the addition of 20.

It will be noted that the base member 300 is provided adjacent its upper end with screw threads 360 to receive a threaded plug 382 having an inwardly directed flange 384 to overlie the upper edge of the insulator 315 to clamp the component parts of the spark plug in assembled relation. The inner electrode 306 is provided adjacent its upper end with a threaded portion 386 to receive a threaded member 388 to engage the insulator 314 and maintain the upper portions of the plug in the assembled relation. This plug may be readily disassembled for cleaning purposes or for the replacement of new elements.

The wire 375 may be connected through the resistor or contactor 361 with the central electrode 306, and the wire 377 may be connected to the outer electrode 326 as illustrated. The housing 381 is provided with a threaded ring 390 to which the wire 377 may be connected. The ring 390 may be screwed onto the threaded portion 330 of the outer electrode 326 to securely seal the upper end of the spark plug assembly.

If desired a shield may be positioned on the spark plug where the dual electrode plugs are employed without the transformers, and the high voltage current is transmitted to one of the electrodes of the spark plug. Fig. 20 illustrates one desirable form of shield 401 having a threaded end section 403 adapted to receive a furl 405 surrounding the casing 379 having the current carrying wires 375 and 377 housed therein. If desired the casing 401 may be split and have overlapping edges to securely seal the upper end of the spark plug against the entrance of moisture. The shield may be formed at the bottom end with an inwardly directed flange 407 to overlie the housing 381 of the embodiment illustrated in Fig. 19.

Fig. 21 illustrates a modified form of resistor element adapted to be interposed between one of the electrodes of the spark plug and the wire 411 connected to a transformer associated with the spark plug or to a high tension wire, where separate transformers are not employed at the spark plugs, as illustrated in one form of the embodiments of the invention illustrated in Figs. 11 to 14. A removable and replaceable resistor element 413 may be interposed between the electrode and a shell 415, connected to the wire 411, and shaped to receive the resistor 413. A spring 417 yieldingly urges the resistor 413 into engagement with the electrode 406 of the spark plug. The resistor 413 may be removed and replaced by resistors of different lengths to vary the resistance, or resistors formed of different material but of the same length may be employed to vary the resistance introduced. The resistor 413 may advantageously be formed of carbon, powdered metal, tungsten or other suitable material.

Fig. 22 illustrates a further modified form of resistor wherein a resistor element 421 having a groove 423 formed adjacent one end is provided with a spring clip 425. The spring clip 425 may be introduced into a cylinder 427 formed in a threaded member 431 operably connected to one of the electrodes 406 of the spark plug. Resistors of this type may be formed of different material to provide the desired variation of resistance, and may also be formed of different lengths to provide the desired operating characteristics.

Figs. 23 and 24 illustrate a further modified form of spark plug having spaced parallel electrodes 435 and 437. The electrodes are positioned in a threaded base member 439 adapted to be secured in the cylinder of an engine to position the spark gap forming portions 441 and 443 of the electrodes 435 and 437 respectively in the combustion chambers of the engine.

The electrodes 435 and 437 may be insulated from each other and from the base member 439 and engine by any suitable form of insulating material such for example as stacked mica disks 445. It will be apparent that the lowermost disk 25 is supported on shoulders 447 formed in the base member 439 and in the lower shanks of the electrodes 435 and 437. The upper end of the base member 439 is formed with an inwardly directed flange 449 to overlie disks of larger diameter and 30 maintain the plug in the assembled relation.

It will be noted that the electrode 435 is somewhat longer than the electrode 437 to separate their upper ends and prevent short circuiting between the upper ends of the electrodes and to 35 insure the formation of the charge firing spark in the spark gap 451 between the portions 441 and 443 of the electrodes.

A ring 453 is positioned adjacent the top of the electrode 437 and is contoured to overlie a 40 group of the disks 445 and maintain a desired pressure on the disks 445 between it and the flange 449 of the base member 439. The upper end of the electrode 437 is flared outwardly as illustrated at 455 over the ring 453 to insure good 45 electrical contact therewith. The inner portion of the ring 453 may be cut out, and contoured mica or other suitable insulating disks 459 positioned therein as illustrated in Fig. 23.

A ring 461 may be positioned above the smaller 50 disks surrounding the longer electrode 435, and the upper end of the electrode 435 may be flared outwardly as illustrated at 457 to maintain a desired pressure on the upper disks and to insure good electrical contact therewith.

55 A transformer 463 similar to that illustrated in Fig. 7 may be employed with this spark plug, the low intensity contacts from the source of electrical energy being connected with opposite ends of the primary winding. One end of the secondary winding of the transformer may be connected to the electrode 435 through a contactor 467 engaging the ring 461 engaging the electrode 435. The other end of the secondary winding of the transformer may be connected to the electrode 437 through the ring 453, threaded to receive the transformer 463 as illustrated at 465.

It will be understood that if desired this spark plug may be used without the transformer as discussed above.

70 Features disclosed but not claimed herein are being claimed in my copending application Serial Number 50,720 filed September 23, 1948.

I claim:

1. An ignition circuit comprising a battery, 75 spaced induction coils, a rotatable electromag-

net adapted to move with reference to the induction coils, connecting means between the battery and one end of the electromagnet, connecting means between the battery and the other side of the electromagnet, and means to close the circuit between the battery and the electromagnet when the electromagnet is aligned with one of the induction coils.

2. An ignition circuit comprising spaced induction coils, a rotatable member, an electromagnet having a coil carried by the rotatable member to move with reference to the induction coils, a source of electric energy, connecting means between one end of the coil of the electromagnet and said source, a circuit interrupter operated by the rotatable member, connecting means between said source and the circuit interrupter, and connecting means between the circuit interrupter and the other end of the coil of the electromagnet.

3. An ignition system including a spark plug, an induction coil spaced from said spark plug, a circuit including said induction coil and said spark plug as integral parts thereof, and means for causing low tension current to flow in said circuit, said means comprising an additional coil rotatable in a path adjacent said induction coil, and means for supplying current to said rotatable coil.

RAYMOND J. MILLER. 30
